(57) **CLAIM**

The ornamental design for a container boot, as shown and described.

DESCRIPTION

FIG. 1 is a top perspective view of a new, original and ornamental design for a container boot according to one aspect of the present disclosure;

FIG. 2 is a front elevation of FIG. 1;

FIG. 3 is a rear elevation view of FIG. 1;

FIG. 4 is a left side elevation view of FIG. 1;

FIG. 5 is a right side elevation view of FIG. 1;

FIG. 6 is a top plan view of FIG. 1;

FIG. 7 is a bottom plan view of FIG. 1;

FIG. 8 is a bottom perspective view of FIG. 1;

FIG. 9 is a top perspective view of a new, original and ornamental design for a container boot according to another aspect of the present disclosure;

FIG. 10 is a front elevation of FIG. 9;

FIG. 11 is a rear elevation view of FIG. 9;

FIG. 12 is a left side elevation view of FIG. 9;

FIG. 13 is a right side elevation view of FIG. 9;

FIG. 14 is a top plan view of FIG. 9;

FIG. 15 is a bottom plan view of FIG. 9; and,

FIG. 16 is a bottom perspective view of FIG. 9.

The broken lines in the drawings depict portions of the container boot that form no part of the claimed design.

1 Claim, 10 Drawing Sheets
